AUGUST HUND, OF WEST ORANGE, NEW JERSEY, ASSIGNOR TO WIRED RADIO, INC., OF NEW YORK, N. Y., A CORPORATION OF DELAWARE

CASCADE AMPLIFIER

Application filed July 22, 1930. Serial No. 469,805.

My invention pertains in general to cascade amplifiers and specifically relates to a cascade amplifier which employs a photoelectric cell.

5 In my co-pending application, serial number 460,590, filed June 12, 1930, patented June 14, 1932, No. 1,863,052, I have disclosed a photoelectric cell producing a substantially elongated electronic stream under control of an external electrostatic grid.

One of the objects of my present invention consists in providing a cascade amplifier employing a plurality of photoelectric cells having external electrostatic grids.

15 A further object comprises producing a resistance coupled multi-stage amplifier system in which external grids form the controlling electrodes of a plurality of photoelectric cells producing substantially elongated electronic streams.

Another object consists in producing a multi-stage photoelectric cell amplifier system in which the characteristic of each stage of amplification can be altered by adjusting 25 the relative position of the grid and cathode of the photoelectric cell.

I accomplish the above desirable objects in a novel cascade amplifier system employing a photoelectric cell of the type disclosed 30 in my co-pending application before referred to.

In the drawing I have diagrammatically illustrated one embodiment of the cascade amplifier system of my invention.

35 Referring to the drawing, an inductance 1 and capacitance 2 comprise an input circuit for my amplifier system. This input circuit can be tuned to resonance with an alternating input current of definite frequency induced in the inductance 1. It will, of course, be understood that this input circuit is merely indicative of an input source commonly used with multi-stage amplifier systems. Any other suitable source of input current could be equally well employed 45 with my amplifier system.

The input circuit is connected, as shown, to the grid 3 and the cathode 4 of the photoelectric cell 5. The grid 3 is an annular 50 electrode exteriorly positioned on the tubu-

lar containing envelope of the photoelectric cell 5 in a manner adapted to produce an electrostatic field which acts on the electronic stream from the cathode 4 to the anode 6. The cathode and anode are positioned in the envelope so as to produce a substantially elongated electronic stream which can be more readily influenced by the electrostatic field.

55 The anode 6 of the photoelectric cell 5 is directly connected to the grid electrode 7 of another photoelectric cell 8. The anode 9 of the photoelectric cell 8 is directly connected to the grid electrode 10 of another photoelectric cell 11. The cathodes 12 and 13 of the photoelectric cells 8 and 11 are connected in parallel with the cathode 4.

The battery 14, or other suitable source of current, is connected on its negative side to the cathodes 4, 12, and 13. The positive side 60 of the battery 14 is connected in parallel to the resistances 15 and 16, and an indicating device 17. The resistances 15 and 16 are connected to the anodes 6 and 9 respectively, while the indicating device 17 is connected to 65 the anode 18 of the photoelectric cell 11. The resistances 15 and 16 are of a value adapted to provide a suitable potential drop across the anodes and cathodes of the photoelectric cells 5 and 8 respectively. The indicating device 17 can be a telephone, a meter, or any instrument for indicating current flow, or may be a work circuit. A fixed capacitance 19 is connected in parallel with the battery 14 to form a by-pass condenser.

80 85 Such an arrangement in which a plate of one electron discharge device is connected to the grid of a succeeding electron discharge device comprises what is commonly known as a cascade or tandem connection. Cascade or tandem connections for thermionic electron discharge devices used as amplifiers are well known in the art.

When the proper voltages are applied to the interior electrodes of the photoelectric cells of my invention, and when irradiations are directed upon the cathodes thereof, a substantially elongated electronic stream will be produced from cathode to anode in each cell. The annular exterior electrodes 100

serve to control the electronic stream in each cell. It is an especial feature of the photoelectric cell disclosed in my copending application before referred to that the exterior

5 grid electrode can be moved with reference to the interior cathode, thereby altering the characteristic of the photoelectric cell.

A variable current applied at the input circuit 1-2 will set up an electrostatic field 10 at the grid electrode 3 and which acts on the electronic stream produced from the cathode 4 to the anode 6 of the photoelectric cell 5. The electronic stream is therefore influenced in accordance with this electrostatic field.

15 The variations of these electrostatic charges are consequently amplified in the plate current of the photoelectric cell 5. This plate current is directly applied to the grid electrode 7 of the next photoelectric cell 8.

20 The grid electrode 7 influences the electronic stream from cathode 12 to anode 9 to further amplify the variations of the original input current. The output of the photoelectric cell 8 is then applied to the control grid

25 10 of the next photoelectric cell 11. The variations are further amplified in the same manner. The output of the final photoelectric cell 11 is then delivered to the indicating device 17. It will of course be understood

30 that any number of photoelectric cells could be equally well arranged in a similar manner to produce cascade amplification.

It will be noted that the couplings between the photoelectric cells are essentially of the

35 resistance-capacitance type, but that the controlling electrodes, in effect, form the capacitance components of the resistance-capacitance couplings. This arrangement avoids the introduction of extraneous capacitances

40 in the amplifier circuit which are often associated with the connections from such couplings to control grids in usual thermionic amplifier systems.

It will now be obvious that I have provided a novel form of cascade amplifier and that many advantages will be derived from the use of such a system. A particular advantage resides in the feature of adjustment of the grid with reference to the cathode 50 whereby the characteristic of the photoelectric cell can be changed.

Although I have shown a preferred embodiment of my amplifier, it is to be understood that many changes will readily occur 55 to those skilled in the art, but which will not depart from the intended scope of my invention. I do not therefore desire to limit myself to the foregoing except insofar as may be pointed out in the appended claims.

60 What I claim as new and original and desire to secure by Letters Patent of the United States is:

1. An amplifier system comprising, an input circuit, a plurality of photoelectric cells, 65 each of which includes an interior anode, an

interior cathode, and an exterior grid; and an output circuit, said photoelectric cells being directly connected in tandem from plate to grid.

2. An amplifier system comprising, an input circuit, a plurality of electron discharge tubes each of which is adapted to produce photoelectric emission and which are connected in series by resistance-capacitance couplings, the capacitance component of said 75 couplings being adapted to set up an electrostatic field which directly controls said photoelectric emission, and an output circuit for said discharge tubes.

3. An amplifier system comprising, a plurality of electron discharge tubes each having a photosensitive cathode, and an anode adapted to produce a substantially elongated electronic stream, an external control electrode for each of said electron discharge 80 tubes, an input circuit included between the control electrode and cathode of one of said electron discharge tubes, an output circuit included between the anode and cathode of another of said electron discharge tubes, and cascade connections between said electron discharge tubes in which the anode of one tube is directly connected to the control electrode of the succeeding tube, all of said control electrodes being movable whereby said 85 control electrodes can be individually adjusted for best conditions of amplification for said tubes.
